TOY GUN

Leon H. Kirkell, Blairsville, Pa., assignor to Blairs-
ville Machine Products Company, Blairsville,
Pa., a corporation of Pennsylvania

Application June 9, 1948, Serial No. 146,855

Term of patent 3½ years

(Cl. D34—15)

To all whom it may concern:

Be it known that I, Leon H. Kirkell, a citizen of the United States, residing in Blairsville, county of Indiana, and State of Pennsylvania, have invented a new, original, and ornamental Design for Toy Gun, of which the following is a specification, reference being had to the accompanying drawing, forming part thereof.

Fig. 1 is a side elevational view of the toy gun, showing my new design;

Fig. 2 is a top plan view thereof; and

Fig. 3 is a front elevational view thereof looking from the right of Figs. 1 and 2.

I claim:

The ornamental design for a toy gun, substantially as shown.

LEON H. KIRKELL.
